HIS ATTORNEY

UNITED STATES PATENT OFFICE

EARL B. LEAR, OF PHILLIPSBURG, NEW JERSEY, ASSIGNOR TO INGERSOLL-RAND COMPANY, OF JERSEY CITY, NEW JERSEY, A CORPORATION OF NEW JERSEY

VALVE FOR ROCK DRILLS

Application filed December 14, 1928. Serial No. 325,952.

This invention relates to rock drills, but more particularly to a distributing valve for fluid actuated rock drills of the hammer type.

One object of the invention is to obtain a rapid and positive action of the valve for distributing the pressure fluid to the ends of the cylinder.

Other objects will be in part obvious and in part pointed out hereinafter.

In the drawings illustrating the invention and in which similar reference characters refer to similar parts,

Figure 1 is a sectional elevation of a rock drill equipped with a valve constructed in accordance with the practice of the invention, and

Figure 2 is a transverse view taken through Figure 1 on the line 2-2 looking in the direction indicated by the arrows.

Referring more particularly to the drawings, A represents the cylinder of a rock drill having a piston chamber B in which is disposed a reciprocating hammer piston C. The cylinder A has free exhaust ports D which are controlled in this instance by the piston C.

A closure is provided for the front end of the piston chamber B in the form of a front cylinder washer E which has a bore F to slidably receive an extension G of the piston C.

The rearward end of the cylinder A is provided with an enlarged bore H to receive rotation mechanism comprising a rotation ratchet J and the head K of a rifle bar L. The head K is disposed within the rotation ratchet J and carries spring pressed pawls O which are adapted to engage teeth P of the rotation ratchet J for controlling the direction of rotation of the rifle bar L.

The rifle bar L is provided with the usual flutes Q which may slidably interlock with the piston C in a well known manner for imparting rotary movement to the piston and thus through the medium of suitable chuck mechanism (not shown) to the working implement against which the piston is adapted to strike.

The rotation ratchet J may be secured in

position in any suitable manner. In the present instance it forms a seat for a back head R which may be secured to the cylinder A by means of the usual spring pressed side bolts (not shown). In the construction shown the back head R serves as a closure for the rearward end of the cylinder and forms a housing for a throttle valve S whereby the admission of pressure fluid into the drill may be controlled. The throttle valve S may be of the rotary type and accordingly has a lever T whereby it may be manipulated.

In the present instance the throttle valve S is provided with a central chamber U which may be in constant communication with a source of pressure fluid supply through a suitable coupling or other device (not shown).

In the wall of the throttle valve S is a port V which registers with a passage W in the back head leading to a supply reservoir X in the front or inner end of the back head R.

In accordance with the present invention a valve mechanism designated generally by Y is disposed in the innermost end of the bore H adjacent the piston chamber B to control the admission of pressure fluid into the ends of the piston chamber.

The valve mechanism comprises a valve chest Z consisting in this instance of plates b, c and d. The plate d is in the form of a back cylinder washer and serves as a closure for the rearward end of the piston chamber B.

The plate c is interposed between the plates d and b and in the plate b is formed a valve chamber e for the reception of an oscillatory plate distributing valve f which has a central fulcrum g whereon said valve is adapted to rock from one limiting position to another.

The valve f has a pair of wings h and j. The wing h in this instance controls the flow of pressure fluid into the rearward end of the piston chamber B through a rearward inlet passage k leading to the rearward end of the piston chamber B and the admission of pressure fluid to the front end of the piston chamber through an inlet passage o. The inlet passages k and o lead from the same end of the valve chamber.

At the right hand end of the valve chamber e as Figure 1 is viewed in the drawings is a

recess *p* having portions lying on opposite sides of the valve chamber *e* and into this recess *p* extends the end of the wing *j* of the valve. Pressure fluid for actuating the drill 5 is introduced into the recess *p* through ports *q* and *r* which afford communication between the recess *p* and a passage *s* leading from the supply reservoir *X*. The port *q* in this instance is located near the rearward end of the 10 valve chamber *e* and the port *r* at a point forwardly of the valve chamber *e* so that pressure fluid entering these ports will strike the rearward and front surfaces of the wing *j* of the valve. The edge of the wing *j* is spaced 15 from the wall of the recess *p* so that a clearance *t* exists between the end of the valve and the outer wall of the recess *p*.

At the opposite end of the valve chamber *e* is a cavity *u* into which extends the wing *h* 20 of the valve and a clearance *v* exists between the end of the wing *h* and the outer wall of the cavity *u* so that pressure fluid may flow over the end of the wing *h* from one side of the cavity to the other. The pressure fluid 25 for supplying the inlet passages *k* and *o* is conveyed to the cavity *u* by a pair of passages *w* and *x* leading from the valve chamber *e* at a point adjacent the recess *p* to the cavity *u*. The supply passage *w* in this instance lies 30 above the valve chamber *e* and the supply passage *x* lies below the valve chamber *e*.

The following is a brief description of the operation of the valve: With the wing *j* of the valve *f* seated on the plate *c* as illustrated 35 in Figure 1, pressure fluid flowing through the ports *q* and *r* into the recess *p* will flow over the seated end of the valve into and through the supply passage *w* and over the wing *h* into the cavity *u*, thence through the 40 inlet passage *k* into the rearward end of the piston chamber *B* to drive the piston *C* forwardly. During this course of the pressure fluid, the pressure above the wing *j* may be a trifle lower than that in the forwardmost part 45 of the valve chamber *e* so that pressure fluid will be constantly flowing over the end of the wing *j* to exert a suction thereon tending to tilt the valve. At the same time the pressure fluid flowing over the wing *h* will also exert 50 a suction thereon so that when the piston *C* overruns the port *D*, these forces acting on the wings of the valve will immediately throw the valve to its other limiting position.

In the absence of means for relieving the 55 compression in the ends of the piston chamber, the compression created during the forward stroke of the piston will flow through the inlet passage *o* to act against the rearward surface of the wing *h* for augmenting the 60 forces acting against the wings of the valve for throwing the valve.

With the valve in the new position, pressure fluid will flow from the recess *p* across the forward surface of the wing *j* into the 65 supply passage *x* thence into the cavity *u* and

over the end of the seated wing *h* into the inlet passage *o* and thence into the front end of the piston chamber *B* for driving the piston *C* rearwardly. The compression created in the rearward end of the valve by the piston will then act through the inlet passage *k* 70 against the forward surface of the wing *h*. At the same time the pressure fluid flowing from the rearward end of the recess *p* across the end of the wing *j* and the pressure fluid flowing over the wing *h* will exert a suction on the valve which, together with the compression acting through the inlet passage *k*, will throw the valve *f* to its initial position. 75

I claim:

1. In a fluid actuated rock drill, the combination of a cylinder and a piston, an exhaust port for the cylinder, a valve chest having a valve chamber, inlet passages leading from the valve chamber to the cylinder, an oscillatory plate valve in the valve chamber to control the inlet passages, and ports and passages in the valve chest for conveying pressure fluid over both ends of the valve during its course to the inlet passages, thus exerting a suction on both ends of the valve tending to throw the valve from one limiting position to the other. 80

2. In a fluid actuated rock drill, the combination of a cylinder and a piston, an exhaust port for the cylinder, a valve chest having a valve chamber, ports in the valve chest affording communication between one end of the valve chamber and a source of pressure fluid supply, supply passages in the valve chest for conveying pressure fluid from one end of the valve chamber to the other, inlet passages leading from the last mentioned end of the valve chamber to the cylinder, and a valve in the valve chamber for controlling the inlet 95 openings of the supply and inlet passages. 100

3. In a fluid actuated rock drill, the combination of a cylinder and a piston, an exhaust port for the cylinder, a valve chest having a valve chamber, ports in the valve chest affording communication between one end of the valve chamber and a source of pressure fluid supply, supply passages in the valve chest for conveying pressure fluid from one end of the valve chamber to the other, inlet 110 passages leading from the last mentioned end of the valve chamber to the cylinder, and an oscillatory plate valve for controlling the supply passages and the inlet passages, said valve being exposed simultaneously at both ends to the suction of the pressure fluid flowing thereover into the inlet passages for throwing the valve. 115

4. In a fluid actuated rock drill, the combination of a cylinder and a piston, an exhaust port for the cylinder, a valve chest having a valve chamber, a recess at one end of the valve chamber constantly exposed to pressure fluid, a cavity at the other end of the valve chamber, supply passages in the valve chest 120 125

for conveying pressure fluid from the recess to the cavity, inlet passages leading from the cavity to the cylinder, and an oscillatory plate valve in the valve chamber for controlling communication between the recess and the supply passages and between the cavity and the inlet passages.

5. In a fluid actuated rock drill, the combination of a cylinder and a piston, an exhaust port for the cylinder, a valve chest having a valve chamber, a recess at one end of the valve chamber constantly exposed to pressure fluid, a cavity at the other end of the valve chamber, supply passages in the valve chest for conveying pressure fluid from the recess to the cavity, inlet passages leading from the cavity to the cylinder, and an oscillatory plate valve in the valve chamber having a pair of wings, one of said wings controlling communication between the recess and the supply passages and the other wing controlling communication between the cavity and the inlet passages.

In testimony whereof I have signed this specification.

EARL B. LEAR.
